LAMP CONSTRUCTION

Samuel Sher, Chicago, Ill.

Application March 24, 1938, Serial No. 197,778

4 Claims. (Cl. 240—81)

This invention relates to lamp construction, and particularly to a lamp wherein a guide or night light is embodied in its construction.

One object of the present invention is to provide a lamp structure having the usual service lights for ordinary use, and wherein small light bulbs of low current consumption are positioned in the pedestal of the lamp to provide sufficient illumination for one to see objects and move about a room in safety when the service lights are turned off.

Another object of the invention is to so mount or position the small light bulbs in the pedestal to facilitate their renewal, or the making of other repairs, as may be found necessary.

Another object of the invention is to provide a novel construction and arrangement whereby sufficient light may be obtained from the small bulbs for the purpose intended, and yet not of such volume or character as to be annoying, as for example, to one sleeping in the same room.

Another object of the invention is to provide a novel arrangement whereby the service lights and the small lights may be connected to the same source of current supply, and wherein one or several of the small lights, or the service lights may be operated independently of each other, as desired.

Another object of the invention is to provide a novel construction and arrangement wherein the light bulbs are positioned sufficiently remote from floor coverings, such as rugs or the like, to eliminate fire hazards, and wherein suitable ventilation is provided adjacent the light bulbs.

A further object of the invention is to provide a lamp having a pedestal of pleasing appearance wherein the mounting for the small light, and the securing means therefor are so arranged as to appear as a portion of the pedestal structure.

A still further object of the invention is to improve a device of the character described in sundry details hereinafter referred to and particularly pointed out in the appended claims.

One embodiment of the present invention is shown for illustrative purposes in the accompanying drawing, in which:

Fig. 1 is an elevational view of a floor lamp embodying features of the present invention;

Fig. 2 is a sectional elevational view of a portion of the structure illustrated in Fig. 1, and taken substantially as indicated by the line 2—2 of Fig. 3;

Fig. 3 is a plan sectional view taken substantially as indicated by the line 3—3 of Fig. 2; and

Fig. 4 is a diagrammatic view of the wiring circuit for operating the lamps employed in the present structure.

As illustrated in the drawing, the present invention is shown in relation to a floor lamp comprising a base member 5 having a pedestal indi-

cated, as a whole, by the numeral 6 mounted thereon, and having a main lamp socket 7 adjacent the upper end portion thereof adapted to receive service lights or bulbs 8 of usual size adapted for ordinary use, and supplied with current from line wires 9 and 11 (Fig. 4) by means of the lamp circuit wires 12 and 13 extending upwardly through a conduit 14 positioned within the pedestal 6, as clearly illustrated in Figs. 1, 2, and 3 of the drawing.

The pedestal 6 is shown, in the present instance, as comprising an elongated hollow tubular member indicated, as a whole, by the numeral 15 and comprising, preferably, a plurality of relatively short members or sections shown as spacers 15a and lamp housings or breaks 15b, the portions or breaks 15b being, preferably, of relatively greater diameter than the spacers 15a and provided, respectively, with openings 16 (Fig. 2) of substantially like construction formed in the wall portion thereof, and having lugs 17 provided with screw threaded apertures 18 formed on the tubular member, preferably adjacent the upper end portion of the openings 16.

Removably mounted in the respective openings 16, are panels indicated, as a whole, and respectively, by the numerals 19, 21, and 22, the panel 21, for example, being clearly illustrated in Fig. 3 as of substantially semi-circular cross section to be positioned in the opening 16, the lower portion of which extends substantially halfway around the housing or break 15b, and shown in Fig. 2 as provided with a retaining lug 23 adjacent its lower edge portion adapted to be positioned within the housing 15b to secure the panel 21 against accidental displacement with respect to the pedestal, the upper end portion of the panel 21 having an aperture 24 formed therein adjacent the lug 23 and adapted to receive fastening means shown, in the present instance, as a screw 25 engageable with the threaded aperture 18 of the lug 23 for securing the panel within the opening 16 formed in the lamp housing or break 15b.

Mounted within the member 15b, preferably, on the inner side of the panel 21, by means of spot-welding, indicated at 26, or by other suitable means, is a bracket 27 having an electrical socket 28 mounted therein adapted to receive a relatively small light bulb 29, preferably of low current consumption and operatively connected by means of conductors 31 with the circuit connecting the relatively larger bulbs 8 with the line wires 9 and 11, for operating the smaller lights.

Formed also in the tubular member 15, preferably adjacent the respective openings 16, are a plurality of series of apertures 32 through which light from the small bulbs 29 may be emitted for providing a dim light to enable one

to move about the room with safety even though the main or larger lights 8 may not be lighted. It will be observed that by such an arrangement of the apertures 32, direct rays from the lamp 5 29 will be avoided and eliminate discomfiture to occupants of the room, and that the apertures 32 also provide suitable ventilation for the lamp housings or breaks 15b.

By references to Figs. 1 and 4, it will be noted 10 that a switch member or mechanism 33 may be provided for controlling the operation of the lamps 8, and that a switch mechanism 34 is provided whereby one or several of the relatively smaller bulbs 29 may be lighted, regardless of 15 the condition of the bulbs 8.

It will be observed by reference to Figs. 1 to 3 20 that the lamp housing or member 15b is provided with certain ornamentation, as, for example, ribs 35 and knobs 36, and that by providing ribs 20 37 and knobs 38 on the panels 19, 21, and 22, the appearance of the removable panels in the openings 16 of the tubular members as being separate elements is practically eliminated, and that by using screws 25, having head portions of a 25 shape and size substantially like the knobs 38, the fastening means also bears a close resemblance to the ornamental knobs 36 formed on the member 15b and the knobs 38 on the panel, thereby further rendering the panel construction 30 and arrangement inconspicuous to the casual observer.

As previously stated, the pedestal 6 is made up of relatively narrow spacers 15a and wider lamp housings or breaks 15b, and as clearly illustrated 35 in the drawing, a plurality of translucent or transparent plates or disks 39 formed, preferably, of glass or the like are positioned between the respective adjacent end portions of adjacent spacers 15a and housings 15b, as clearly illustrated in Fig. 2, each of the disks 39 being provided with centrally located apertures 41 adapted to receive the conduit 14, and with a boss 29a adapted to enter an adjacent end of a spacer 15a, the disks 39 being provided also with annular flanges 42 forming a recess in one side of the disks adapted to receive adjacent end portions of the housing 15b, thereby providing suitable means for maintaining the housing in relatively fixed position with respect to the conduit 50 14.

It will be observed that by such an arrangement, light from the bulbs 29 may be emitted through the disks 39 between the outer and inner portions of the spacers 15a and housings 15b, respectively, at both the upper and lower portions of the housing to provide a dim light adjacent the lamp and to add to the attractive appearance thereof, it being understood that the translucent material of the disks 39, if desired, 60 may be of various colors to suit the taste of the user.

It will be observed from the foregoing description that the present invention provides a novel construction and arrangement wherein a lamp 65 having the usual service lights for ordinary use is provided with a plurality of relatively small light bulbs of low current consumption, which may be operated regardless of the condition of the service lights, and which are positioned to 70 give a relatively dim light adjacent the lamp structure.

It will be observed also that the manner of mounting the small lights facilitates their renewal, or the making of other repairs, and that the panel structure and arrangement contributes materially to the uniform appearance of the 5 pedestal structure as a whole.

Obviously, the present invention is not limited to the precise construction and arrangement shown and described as the same may be variously modified. Moreover, all the features of the 10 invention need not be used conjointly as the same may be used to advantage in variously different combinations and sub-combinations.

What I claim as new and desire to secure by Letters Patent is:

1. A lamp comprising a base, a vertically disposed pedestal mounted thereon and comprising a plurality of elongated hollow tubular members, certain of said members having openings formed in their respective wall portions and spaced longitudinally of the pedestal at various substantial distances above said base, said certain members having a plurality of series of annularly spaced apertures formed therein between the bottom thereof and the respective openings, a plurality 20 of panels removably mounted, respectively, in said openings and forming closures therefor, and a lamp socket mounted on each of said panels within said certain tubular members.

2. A lamp comprising a base, a vertically disposed pedestal mounted thereon and comprising a plurality of elongated, aligned tubular members of relatively different diameters, a plurality of translucent disks positioned, respectively, between adjacent ends of said members, certain of said members having openings formed therein, panels removably mounted in the respective openings and forming closures therefor, and a lamp socket mounted on each of said panels within 30 certain members.

3. A lamp comprising a base, a vertically disposed pedestal mounted thereon and comprising a plurality of elongated hollow members of relatively wide and narrow diameters, a plurality of translucent disks positioned, respectively, between 40 adjacent ends of said wide and narrow members, certain of said members having openings formed therein, panels removably mounted in the respective openings and forming closures therefor, and a lamp socket mounted on each of said 50 panels within said certain members.

4. A lamp comprising a base, a vertically disposed pedestal mounted thereon and comprising a plurality of elongated hollow members of relatively wide and narrow diameters forming chambers positioned lengthwise of the pedestal, said wide and narrow members being positioned in axial alignment and alternately lengthwise of the pedestal, a plurality of translucent disks positioned, respectively, between adjacent ends of said 60 wide and narrow members, said wide members having openings formed therein, panels removably mounted in the respective openings and forming closures therefor, a lamp socket mounted on each of said panels within said relatively wide members, and means operatively related to said translucent disks and tubular members for retaining the members and disks against relative displacement with respect to each other.
